DESIGN FOR A PARKING METER CASING

Robert Broussard and Charles A. Toce, Houston,
Tex., assignors to Parkrite Corporation, Hous-
ton, Tex., a corporation of Texas

Application September 14, 1937, Serial No. 71,606

Term of patent 14 years

To all whom it may concern:

Be it known that we, Robert Broussard and Charles A. Toce, citizens of the United States and residing in Houston, in the county of Harris and State of Texas, have invented a new, original, and ornamental Design for a Parking Meter Casing, of which the following is a specification, reference being had to the accompanying drawing, forming a part thereof.

Fig. 1 is a side elevational view of a parking meter casing, showing our new design.

Fig. 2 is a front elevational view thereof.

Fig. 3 is a rear elevational view of the same.

We claim:

The ornamental design for a parking meter casing substantially as shown.

ROBERT BROUSSARD.
